US00D991738S

(12) **United States Design Patent** (10) **Patent No.:** **US D991,738 S**
(45) **Date of Patent:** **** Jul. 11, 2023**

(54) **LID OF SPORT BOTTLE**

(71) Applicant: **NINGBO SMART HOUSEWARE CO., LTD**, Ningbo (CN)

(72) Inventor: **Yangyang Zhao**, Ningbo (CN)

(73) Assignee: **NINGBO SMART HOUSEWARE CO., LTD**, Ningbo (CN)

(**) Term: **15 Years**

(21) Appl. No.: **29/812,237**

(22) Filed: **Oct. 20, 2021**

(30) **Foreign Application Priority Data**

Apr. 26, 2021 (CN) 202130243106.5

(51) **LOC (14) Cl.** **07-99**

(52) **U.S. Cl.**

USPC **D7/392.1; D7/391; D7/392; D9/449**
